UNITED STATES PATENT OFFICE

170,931

MICROSCOPE ILLUMINATOR

Michael Macaluso, Jr., Rochester, N. Y., assignor
to Bausch & Lomb Optical Company, Rochester,
N. Y., a corporation of New York

Application June 11, 1953, Serial No. 25,451

Term of patent 14 years

(Cl. D57—1)

To all whom it may concern:

Be it known that I, Michael Macaluso, Jr., a citizen of the United States and a resident of Rochester, county of Monroe, and State of New York, have invented a new, original, and ornamental Design for a Microscope Illuminator, of which the following is a specification, reference being had to the accompanying drawing, forming a part hereof.

Fig. 1 is a front perspective view of a microscope illuminator showing my new design.

Fig. 2 is a rear perspective view thereof showing the other side of the illuminator.

The essential features of my design are shown in full lines on the drawing.

I claim:

The ornamental design for a microscope illuminator, substantially as shown and described.
MICHAEL MACALUSO, JR.
